ATTORNEY

UNITED STATES PATENT OFFICE

ROBERT M. SPARKS, OF DAYTONA BEACH, FLORIDA

ELECTRICAL HEATING DEVICE

Application filed May 21, 1930. Serial No. 454,402.

My present invention has reference to an electrical heating device primarily designed for use in connection with boilers, water heaters, radiators and like plants or devices, 5 but, of course, susceptible for use in various other connections.

The primary object of the invention is the provision of an electrical heater which shall be of a comparatively simple construction, 10 cheaply manufactured, easily assembled and which shall be safe in use as the same is protected from any liability of short circuit.

A still further object is the provision of a heating device that includes an outer metallic cylinder designed to contain therein an oil or other insulating material, the said cylinder having tightly fixed to the open mouth thereof an insulator top provided with a vent opening for the expansion of the oil, a 15 spirally grooved core of porcelain or the like in whose groove there is arranged the coil heating element, insulator spacer members for holding the core and the element from contact with the casing, a conductor 20 rod which passes through the insulator top and the upper spacer element and to which one of the end wires of the coil is connected, the said conductor being surrounded by a porcelain tube to protect the same, a second 25 and longer conductor which passes centrally through the top, the core and both of the spacer elements and to which the second end of the coil is connected, the portion of the last mentioned conductor above the upper 30 spacer element being surrounded and protected by a porcelain tube and both of the conductors affording terminals for the circuit wires.

A further object is the provision of a heater element which may be arranged either 35 vertically, horizontally or angularly in a boiler, water heater or the like.

The invention will be fully and comprehensively understood from a consideration 40 of the following detailed description when read in connection with the accompanying drawings which form part of the application, with the understanding, however, that the improvement is capable of extended application and is not confined to the exact

showing of the drawings nor to the precise construction described and, therefore, such changes and modifications may be made therefrom as do not affect the spirit of the invention nor exceed the scope thereof as 55 expressed in the appended claims.

In the drawings:

Figure 1 is an approximately central vertical longitudinal sectional view through the device. 60

Figure 2 is a top plan view thereof.

Figure 3 is a sectional view on the line 3-3 of Figure 1.

In the drawings the numeral 1 designates the metallic cylindrical casing of the improvement. The casing has a closed bottom and an open top. In the showing of the drawings I have screwed around the open top of the casing 1 a ring flange 2 which may be either of metal or of insulating material and secured to the flange 2, by set screws 3, there is the insulator top 4 of the device. 65

In the showing of the drawings the casing 1 is partly filled with an oil 5. The oil, 75 of course, is in the nature of an insulator and in lieu of the oil any other desirable insulating material may be employed. The top 4 has a vent opening 6 to permit of the expansion of the oil 5 when the same becomes heated in a manner which will presently be described.

In the casing 1, below the level of the oil 5, and also at a suitable distance above the closed bottom of the said casing there are 85 arranged combined insulator and spreader members 7 and 8, respectively. Preferably and as disclosed by the drawings these members are substantially cross-shaped in plan, that is, each of the members has its body formed with extensions 9 whose edges are rounded and each of the extensions 9 is provided with an opening 10. Also the center of each of the members 7 and 8 is provided with a round opening. 90

Between the insulator members 7 and 8 there is arranged a spirally grooved core 11 of porcelain or the like, and in the groove of the core there is arranged the spirally wound heater element 12. The lower and 105

straight end of the heater element 12 passes through one of the openings 10 in the lower member 8. There is arranged on the lower terminal a brass or like rod 13 that passes 5 through the central openings in the members 7 and 8, through a central opening in the core and through a central opening in the insulator top 4. This end of the heater element is clamped between lock nuts 14, 10 respectively, which are screwed on the lower end of the rod 13.

It is to be noted that the members 7 and 8 have their outer edges disposed slightly away from the inner wall of the casing 1 15 and that the spaces between the right angular extensions 9 and the said members 7 and 8 and likewise the openings 10 permit of the passage of the oil or like insulator 4 therethrough.

20 Surrounding the portion of the rod 13 that is arranged between the upper member 7 and the top or closure 5 there is a porcelain tube 15 and this tube is held in tight contact with the said member 5 and with 25 the top 4 through the medium of a binding nut 16 which is screwed on the upper or outer end of the rod. Another binding nut 17 is also screwed on the rod and these nuts grip therebetween the return wire 18 for 30 the source of electricity.

The upper straight end of the wire providing the heating coil 12 is clamped between binding nuts 19 that are screwed on the lower end of a copper or like rod 20 which 35 passes through one of the openings 10 in the upper insulator spacer member 17 and through an opening in the insulator top 4 of the improvement. The rod 17 is surrounded by a porcelain tube 21 arranged between the member 7 and the inner face of the insulator top 4 and the tube is held in tight gripping engagement with the said members 4 and 7 through the medium of a binding nut 21 which is screwed on the outer 40 end of the conductor rod 20. A second and outer binding nut 22 is screwed on the said outer end 23 of conductor rod 20 and between the nuts 21 and 22 there is clamped the end 24 of a conductor that is connected 45 with a source of power for directing electricity through the conductor 20 and through the coil 12, the rod 13 being in the nature of a return conductor.

With my improvement it will be seen that 50 the conductor rods 20 and 13 are held spaced from the insulator tubes 20 and 15 and from the insulating material 5 in the casing 1. It will be further noted that there is no danger of short circuiting the device regardless 55 of the position in which it is arranged as the insulator members 7 and 8 hold the core 11 and the coil 12 from any liability of contact with the metal casing 1. It will be apparent that the electric current passing 60 through the coil 12 will generate heat and

diffuse the same into the surrounding air. The oil, mica or other non-electric conductor 5 in the casing provides an additional heat retaining and heat diffusing means so that water or other substance can be quickly 75 heated by the device when the casing thereof is immersed therein. The spirally grooved porcelain or glass core 11 prevents the sagging or bending of any part of the heating element 12 and it will be noted that 75 there are only two connections for the heating element 12, the same being the rods 20 and 13, and as these rods are connected by lock nuts the possibility of the same becoming loosened and the short circuiting of the 80 device is reduced to a minimum and also that with my construction a number of parts ordinarily employed are eliminated. It will be further noted that should the heating element burn out or become broken it cannot 85 contact with the brass conductor rod 13 so that any liability of short circuiting in this particular instance is also effectively overcome. It will be further noted that by placing the return electric current through the 90 metal conductor rod 13, which is arranged in the center of the insulator core 11, a saving of space is effected. It will be further apparent that the casing 1 is air-tight and that the lubricant 5, in addition to the function 95 therefor above set forth acts as a preserver for the resistance coil to prevent the same readily burning out and consequently preserve the life thereof.

When the device is arranged horizontally or angularly the vent 6 is placed at any convenient location either on the top or in the body of the casing 1.

Having described the invention, I claim:

1. An electrical heater including a metallic casing having an insulating substance therein and having an insulator top, a spirally grooved porcelain core in the casing, insulator spacer elements contacting with the ends of the heater, a heater coil in the groove, a metal rod extending through the spacer elements, the core and the top of the casing, binding nuts on the ends of the rod, the lower binding nuts securing therebetween one end of the heater coil and the upper binding nuts being connected with an electric conductor, a porcelain tube surrounding the portion of the rod above the upper spacer member, a conductor rod between the upper spacer member and the top, binding nuts on the ends thereof, the inner binding nuts being connected to the second end of the coil and the outer binding nuts being connected to the second wire of the conductor. 120

2. An electric heater including a metal casing having a substance of insulating material therein, an insulator cover removably secured to the open end of the casing and having a vent port therethrough, upper and 130

- lower insulator substantially cross-shaped spacer members in the casing having openings in the branches thereof, a spirally grooved porcelain core between the spacer members, a spirally wound heating wire in the groove, a conductor rod between the upper spacer member and the top, binding nuts on the ends of the said rod, the lower binding nuts being connected to one end of
- 5 a heater coil and the upper nuts being connected to a source of electricity, a porcelain sleeve surrounding the rod, a second and longer rod extending centrally through the core, the spacer members and the top, binding nuts on the ends thereof, the lower binding nuts clamping the second end of the heater coil therebetween and the outer binding nuts clamping the return wire for the source of electricity therebetween.
- 10 20 3. An electric heater including a metallic casing having an insulator substance therein partly filling the same, a flanged ring screwed on the mouth of the casing, a top of insulating material arranged over the ring, set screws securing the top to the ring, upper and lower substantially cross-shaped spacer members of insulating material, having openings adjacent to the ends thereof, a spirally grooved porcelain core between the
- 15 25 30 35 40 45 50 spacer members, a metal rod between the upper spacer member and the top having binding nuts screwed on the ends thereof, the inner binding nuts clamping therebetween one end of the heater coil and the outer binding nuts clamping therebetween a conductor from a source of electricity, a porcelain tube surrounding the rod and arranged between the top and the upper spacer member, a metal conductor rod passing centrally through the core, the spacer members and the top, binding nuts screwed on the ends of said rod, the lower binding nuts clamping therebetween the lower or second end of the heater coil and the upper binding nuts clamping therebetween a return wire for the source of electricity and a porcelain sleeve arranged between the upper spacer member and the top and surrounding the portion of the last mentioned rod extending beyond the upper spacer member and said heater having a vent opening.

In testimony whereof I affix my signature.
ROBERT M. SPARKS.
